PEN HOLDER

Richard K. Enseki, Glen Rock, and Michael P. Arnone,
Fairview, N.J., assignors to Kreisler Manufacturing
Corporation, North Bergen, N.J.

Filed Sept. 4, 1970, Ser. No. 24,852

Term of patent 14 years

Int. Cl. D19—02

U.S. Cl. D74—5

FIG. 1 is a front elevational view of a pen holder showing our new design.

FIG. 2 is a side elevational view thereof.

FIG. 3 is a rear elevational view thereof.

FIG. 4 is a top plan view thereof.

The bottom of the pen holder is plain.

We claim:

The ornamental design for a pen holder, substantially as shown and described.
